UNITED STATES PATENT OFFICE.

EDMUND DZIUK, OF DETROIT, MICHIGAN.

COMBINATION POST CARD AND LETTER.

Application filed December 26, 1925. Serial No. 77,798.

My invention relates to a new and useful improvement in a combination post card and letter and has for its object the provision of a post card combined with a sheet of writing paper so that the user will have the convenience of the post card for correspondence and the capacity of a letter size for writing upon.

Another object of the invention is the provision of a cardboard back with a flexible sheet or number of sheets attached to the address side so that a large amount of correspondence may be written upon the post card and the rear side of the post card used for printing a picture or the like thereon.

Another object of the invention is the provision of a flexible sheet attached to a stiff back member which serves as a post card, the flexible sheet having affixing means so that it, when used as a correspondence sheet may be folded upon the card to conceal the correspondence and attached in this concealing position.

Other objects will appear hereinafter.

The invention consists in the combination and arrangement of parts hereinafter described and claimed.

The invention will be best understood from a reference to the accompanying drawings, which form a part of this specification and in which

Fig. 1 is a plan view of one form of the invention.

Fig. 2 is a fragmentary plan view of another form of the invention.

Fig. 3 is a plan view of the invention.

Fig. 4 is a plan view of another form of the invention.

Fig. 5 is a fragmentary elevational view of another form of the invention.

Fig. 6 is a sectional view taken on substantially line 6—6 of Fig. 2.

In the form shown in Fig. 1 I have provided a stiff cardboard portion 7 which may be used in the customary manner of postal cards—one-half of the one side being used for the address and the other half being used for correspondence, the reverse side carrying a picture of local interest of the place from which mailed. Connected along its edge to the division line on the post card is a sheet of paper 9 which is positioned over a second sheet 10—each of these sheets serving as a sheet of letter paper upon which the correspondence may be written—the inner surface of the sheet 9 being used for correspondence and both sides of the sheet 10 so that consid-

erable correspondence may be written upon the sheets and concealed by the sheet 9 or cover flap. As shown in Fig. 1 the sheet 9 is provided with a short tongue which projects from the edge thereof and which may be glued to the card portion 7—this tongue 11 being gummed if desired.

In the form shown in Fig. 2 a similar structure is arranged—the card 7' having the address portion 8' and provided with the flexible writing sheets 9' and 10'—the sheet 9' having the tongue 11' projecting therefrom. This structure is the same as shown in Fig. 1 excepting that the flexible writing sheets 70 are connected along their edges along the upper edges of the card 7'.

In the form shown in Fig. 3 the card 16 is connected by means of wires 17 and 18 projected therethrough and doubled over upon a sheet of writing paper which is formed larger than the card 16 and adapted for folding inwardly upon itself on the lines 12 and 14 and again upon itself on the line 15. The flap 19' is provided with the tongue 19 which may be secured to the post card 16 by means of wire clips such as the wire clips 17 or 18 or which may be gummed or pasted to the post card. This structure and arrangement provides a greater capacity than the other forms illustrated and possesses in addition thereto all of the advantages and features heretofore pointed out.

In this structure the address would be written on the back of the flap 19'.

The reverse side of the post card could be utilized to carry the picture or illustration previously mentioned.

In the form shown in Fig. 4 the card 25 carries on one side the flexible writing sheet 20 which has the portions 22 and 24 projecting outwardly from the upper and lower edges of the card 25. This writing sheet comprise these portions serving to carry the correspondence as stated.

In use after the correspondence is written upon the sheet the portion 24 is folded upon the card 25 or upon the portion 20 and the portion 22 folded thereover—the gummed tongue 23 serving to bind these parts in this folded over portion. The back of the portion 22 would serve to carry the address of the card.

In the form shown in Fig. 5 I have indicated the card 8'' as provided with a flap 9'' which is formed arc-shaped—thus indicating that the flap may be of various designs for

special seasonal occasions. The flap 9" is also provided with the securing tongue 11".

It will be noted from Fig. 6 that the flap 11" is doubled upon itself so that the doubled over portion of the flap is glued to the card portion 7', thus permitting the entry of a paper knife or other suitable device between the flap 9' and the card portion 7', so that in detaching the glued end of the flap 9' a portion of the tongue 11' which is glued to the card portion 7' may be severed from the remaining portion of the tongue 11' so that a neat opening of the device may be effected. In this way a mutilation of the sheet 9' upon which the correspondence is written is avoided and the efficiency of the device considerably increased.

These remarks apply to the tongues 11, 23, 11" and 19.

20 In this way I have provided a post card having the features pointed out and providing a greater capacity for correspondence.

The variation in structure is one which is such that little additional cost of manufacture 25 is met and the convenience considerable.

While I have illustrated and described the preferred form of structure, I do not wish

to limit myself to the precise details of structure shown, but desire to avail myself of such variations and modifications as come within 30 the scope of the appended claim.

Having thus described my invention what I claim as new and desire to secure by Letters Patent is:

A combination post card and letter of the class described, comprising: a post card portion formed from comparatively stiff material; a correspondence sheet of larger dimensions than said post card and extending outwardly therefrom at three sides thereof; a centrally positioned flap on said sheet extending outwardly from said card at the remaining side thereof; means for securing said sheet to said card, said sheet being foldable upon itself to a less width than the width of 45 said card, and said flap being foldable over said folded sheet; and a tongue on said flap adapted to be secured to one edge of said card for securing said flap in folded over relation to retain said sheet in folded condition. 50

In testimony whereof, I have signed the foregoing.

EDMUND DZIUK.
